ARM CHAIR

George Alfred Koch, Cobourg, Ontario, Canada, assignor
to Curtis Products Limited, Cobourg, Ontario, Canada

Filed July 24, 1967, Ser. No. 7,960

Term of patent 14 years

U.S. Cl. D15—1
Int. Cl. D6—01

FIG. 2

FIG. 1

FIGURE 1 of the drawings is a perspective view of a chair showing my design, and

FIGURE 2 is a view of the chair of FIGURE 1 from the back.

The design is characterized by the combination of the specifically configured side framing portions and the backrest brace member all in association with the unitized body support cushion as shown.

I claim:

The ornamental design for an arm chair, as shown and described.
